UNITED STATES PATENT OFFICE

ROMAN S. OEHLER, OF CINCINNATI, OHIO

DETACHABLE HANDLE

Application filed June 10, 1930. Serial No. 460,230.

This invention relates to a handle adapted to be attached to and removed from handleless containers whereby such articles may be given an added usefulness.

5 An object of the invention is to provide a handle of the class described which is adjustable to containers of varying shapes and wall thicknesses.

Another object is to provide such a device which is non-removable and non-slipping when in position.

Another object is to provide such a handle which is simple in use and in construction.

These and other objects are attained by the means described herein and set forth in the accompanying drawings, in which:

Fig. 1 is an isometric view of a handle of this invention positioned upon a container.

Fig. 2 is a detail view of the cam plate forming a part of the device shown in Fig. 1.

Fig. 3 is a side elevational view of a modified form of handle in position, parts of the container being broken away.

Fig. 4 is a view on line 4—4 of Fig. 3.

25 Fig. 5 is an isometric view of another modified form of the invention, with part broken away.

The device of the present invention is useful upon any vessel upon which it may be desirable temporarily to attach a handle. It is particularly useful as an article of camp equipment since emptied tins may, by its use, be utilized for drinking, cooking, etc. In this connection it might be pointed out that the 30 later type of can opener provides a smooth, rounded and beaded edge upon opening of the tin, so that the uses above suggested are quite practicable. It is a tin opened in this fashion which has been illustrated in the accompanying drawings.

The handles of this invention are preferably formed of metal strips. The handle 8, in Fig. 1, comprises the upper, substantially straight portion 9 terminating in a downward hook portion 10 disposed at substantially right angles thereto. The lower end 11 of handle 8 is given a slight outward bend. The handle portion intermediate the ends is curved in the usual way to provide for convenient gripping. Portion 9 is perforated as

at 12 for loosely receiving a threaded bolt 13 having the knurled head 14, with, preferably, a contact shoulder 140 therebeneath. A cam plate 15 is disposed beneath portion 9 and threadedly receives bolt 13. Plate 15 may be 55 of the same width as handle 8, is substantially rectangular and has a cut corner 16 at its front end. The threaded perforation 17 is disposed somewhat forwardly of the center. In positioning the handle, plate 15 is turned 60 so as to extend transversely of portion 9, with the cut corner 16 disposed adjacent the tin. The hook 10 is placed over the beaded edge 18 and in abutment with the inner face of the tin. Plate 15 may then be conveniently 65 turned with the forefinger so as to bring the edge 19 of the plate into contact against the outside face of the tin directly beneath the bead 18. Cut corner 16 permits the necessary clearance for this pivotal movement. In this 70 position the rear edge 20 of the plate contacts the curved portion of handle 8, as indicated at 200. Turning of threaded bolt 13 results in firm binding of plate 15 against the tin and the handle. The handle is removed by the 75 reverse process. It should be noted that edge 19 of plate 15, by advancement of bolt 13, is drawn upwardly into binding relationship 80 against head 18, and that the lower end 11 of the handle comes into firm contact with the lower face of the can when the handle is positioned. The relation of plate 15 with the adjacent portions of the handle makes possible a wide range of adjustment to varying types and thicknesses of containers. 85

In the modification shown in Fig. 3, the curve of the handle is carried up higher and a straight vertical section 21 is provided adjacent the upper end. Said end is cut longitudinally so as to provide a pair of tongues 22 and 23 in the same plane as section 21, and an inwardly bent intermediate tongue 24 in spaced relationship with tongues 22 and 23. The lower portion of tongue 24 is threadedly perforated to receive the threaded bolt 25. 95 The bifurcated end thus formed is adapted to engage the top edge of a container with tongues 22 and 23 abutting the inner face of the tin and lying upon opposite sides of the usual seam 26, and the tongue 24 abutting 100

the outer face of bead 18. The bolt 25 is advanced to contact the tin directly beneath bead 18, for securing the handle in position. The association of tongues 22 and 23 with seam 26 precludes lateral movement of the handle.

The modification 30 shown in Fig. 5 is similar in form to the device just described. In this modification, the central tongue 27 is straight and the lateral tongues 28 and 29 are bent forwardly at their points of juncture with the handle. Tongue 27 is likewise provided with tightening bolt 25. The bent portions of tongues 28 and 29 contact the top of beaded edge 18 and the tightening of bolt 25 against the lower edge of said bead results in a rigid positioning of the handle, rendering unnecessary the association of the handle with a vertical seam, as is desirable in the modification previously described. Similar modifications, coming within the spirit of this invention, will become apparent upon consideration of the disclosures herein.

25. What is claimed is:

A detachable handle for containers with top edge beads said handle comprising a body, a perforated overhanging portion having means at its end for engaging the top of a container, a threaded bolt loosely seated in a perforation of the overhanging portion, and a plate member threadedly perforated to receive said bolt and disposed beneath said overhanging portion, said plate being adapted to be pivotally moved to contact the container and said body with opposite ends thereof respectively, the intermediate portion of the plate being free of contact with said body and said plate being adapted to be drawn up at one end by means of said bolt into binding relationship with container beads of various sizes, the opposite end of the plate being held against the body of the positioned handle.

45. In testimony whereof, I have hereunto subscribed my name this 6th day of June, 1930.

ROMAN S. OEHLER.
